UNITED STATES PATENT OFFICE.

HENRY BERGER, OF NEW YORK, N. Y.

DESIGN FOR ESCUTCHEON CENTER-PIECE.

Specification forming part of Design No. 5,213, dated August 22, 1871.

To all whom it may concern:

Be it known that I, HENRY BERGER, of the city, county, and State of New York, have invented a new and original Design for Escutcheon Center-Piece; and I do hereby declare the following to be a full, clear, and exact description thereof, which will enable those skilled in the art to make and use the same, reference being had to the accompanying drawings forming part of this specification, which drawings represent a plan of this design.

The distinguishing feature of this design is an oval center with radiating twists, and inclosed in a string of pearls. This center is surrounded by foliage and arabesques arranged so as to form a two-cornered escutcheon.

In the drawings, A designates a center-piece, composed of an oval center, B, which is ornamented by radiating twists *a* supported by a foliage, *c*, which is inclosed in a string of pearls, *d*.

The space surrounding the oval center-piece B is ornamented by foliage and arabesques, forming a two-cornered escutcheon, C.

What I claim as new, and desire to secure by Letters Patent, is—

1. In a center-piece, the oval center B, ornamented by radiating twists *a* and surrounded by a string of pearls, *d*, as shown and described.
2. The design of the two-cornered escutcheon C, as shown and described.
3. The combination of the oval center B and two-cornered escutcheon C, as shown and described.

This specification signed by me this 8th day of July, 1871.

HENRY BERGER.
